UNITED STATES PATENT OFFICE.

CHARLES E. ALLEN, OF WALLINGFORD, CONNECTICUT, ASSIGNOR TO R. WALLACE & SONS MFG. CO., OF WALLINGFORD, CONNECTICUT, A CORPORATION OF CONNECTICUT.

DESIGN FOR A COCKTAIL-SERVER.

No. 38,112.

Specification for Design.

Patented July 3, 1906.

Application filed May 10, 1906. Serial No. 316,224. Term of patent 7 years.

To all whom it may concern:

Be it known that I, CHARLES E. ALLEN, a citizen of the United States, residing at Wallingford, New Haven county, Connecticut, have invented a certain new, original, and ornamental Design for Cocktail-Servers, of which the following is a specification, reference being had to the accompanying drawings, forming part thereof.

other side elevation at right angles to that shown in Fig. 1.

I claim—

The ornamental design for a cocktail-server, as shown.

CHARLES E. ALLEN.
